US0D1059394S

(12) **United States Design Patent** (10) **Patent No.:** **US D1,059,394 S**
Acevedo (45) **Date of Patent:** **** Jan. 28, 2025**

(54) **DISPLAY SCREEN OR A PORTION THEREOF WITH A GRAPHICAL USER INTERFACE**

(71) Applicant: **AC Carrier Technologies Inc.**, Rosemont, IL (US)

(72) Inventor: **Maximiliano Acevedo**, Chicago, IL (US)

(73) Assignee: **AC Carrier Technologies Inc.**, Rosemont, IL (US)

(**) Term: **15 Years**

(21) Appl. No.: **29/885,950**

(22) Filed: **Mar. 2, 2023**

(51) LOC (15) Cl. **14-04**

(52) U.S. Cl.

USPC **D14/485**

(57) **CLAIM**

The ornamental design for a display screen or a portion thereof with a graphical user interface as shown and described herein.

DESCRIPTION

FIG. 1 is a front view of a display screen or a portion thereof with a graphical user interface showing a first embodiment of my new design; and,

FIG. 2 is a front view of a display screen or a portion thereof with a graphical user interface showing a second embodiment of my new design.

The dashed broken line perimeter in the drawings illustrate a display screen or portion thereof and forms no part of the claimed design. The remaining dashed broken lines in the drawings illustrate portions of the graphical user interface that form no part of the claimed design.
